VAMP FOR A SHOE OR SIMILAR ARTICLE

William Usdin, North Bergen, N. J., assignor to
Swisscraft Embroidery Company, Union City,
N. J., a partnership

Application March 7, 1952, Serial No. 18,810

Term of patent 7 years

(Cl. D7—7)

To all whom it may concern:

Be it known that I, William Usdin, citizen of the United States and a resident of North Bergen, county of Hudson, State of New Jersey, have invented a new, original, and ornamental Design for Vamp for a Shoe or Similar Article, of which the following is a specification, reference being had to the accompanying drawing, forming a part thereof:

Fig. 1 is a top plan view of a vamp for a shoe or similar article showing my new design.

Fig. 2 is a front view of the article shown in Fig. 1.

Fig. 3 is a side view showing how the vamp shown in Fig. 1 appears when applied to the shoe, the broken lines being for illustrative purposes only.

I claim:

The ornamental design for a vamp for a shoe or similar article, substantially as shown and described.

WILLIAM USDIN.
